CHARLES A. HIVELY, OF COALINGA, CALIFORNIA, ASSIGNOR OF ONE-THIRD TO J. H. GREER AND ONE-THIRD TO C. A. HENDSCH, BOTH OF COALINGA, CALIFORNIA.

SUCKER-ROD, TUBING, AND CASING ELEVATOR.

1,288,585.

Specification of Letters Patent. Patented Dec. 24, 1918.

Application filed September 10, 1918. Serial No. 253,384.

To all whom it may concern:

Be it known that I, CHARLES A. HIVELY, a citizen of the United States, residing at Coalinga, in the county of Fresno and State of California, have invented certain new and useful Improvements in Sucker-Rod, Tubing, and Casing Elevators, of which the following is a specification.

My invention relates to that class of devices, especially used in the well-boring art, the function of which is to conveniently and properly handle the sucker-rods, tubing, and well-casing which comprise strings of sections coupled together.

These devices are termed, in the art, elevators, in that they lift and support the strings of rods, tubing or casing for dismemberment, and lift the various sections thereof and hold them in place for coupling or assembling them.

Though my invention is applicable to sucker-rods, well-tubing, well-casing, or to any pipes or rods which require to be handled in sections for dismemberment or assemblage, I shall for convenience, herein describe it in connection with sucker-rods.

In the operation of deep wells, and particularly oil wells, the fluid is raised to the surface by means of a deep-well-type of pump, which is operated by sucker-rods.

It frequently becomes necessary to remove the sucker-rods from, and replace them in the well. This is done by hoisting the rods with a cable, the hoisting exposing convenient sections of the string, which sections are unscrewed or screwed together, by means of suitable couplings.

The rods are taken hold of by the elevator, this being its function.

The objects and advantages of my elevator will hereinafter fully appear, and to attain these, my invention consists in the novel elevator which I shall now describe by reference to the accompanying drawings, in which—

Figure 1 is an elevation of my elevator showing the sucker-rod in place.

Fig. 2 is a vertical section on the line 2—2 of Fig. 1, the sucker-rod being omitted.

Fig. 3 is a horizontal section on the line 3—3 of Fig. 1, the sucker-rod being omitted.

Fig. 4 is an elevation with the latch member lifted.

The elevator comprises the body-member

1, the latch-member 2, and the link-member 3.

The body-member is a single, relatively heavy and rigid block, provided with a radial groove 4, opening out at the side, and extending through the block from top to bottom. The side lips of the groove are preferably beveled as at 5, in order to better guide the entering rod. The top of the body member is provided, at each side of the groove, with the guide lugs 6, from which spring the side ears 7 in which the link member 3 is articulated. The latch-member 2 is also a single rigid block, pivotally connected with and playing upon one of the guide lugs 6, by a bolt, 8. Said latch-member has a radial groove 9 which extends from top to bottom and opens out at the side. The outer end of the groove plays upon the other guide lug 6 of the body member, so that when the latch-member is down on its seat on the top of the body-member it is locked against lateral movement.

The grooves 4 and 9 of the body-member and of the latch member respectively, are in planes at right angles to each other, but their base portions are alined, when the latch-member is down on its seat on top of the body member.

The link-member 3 is a single U-shaped piece, the ends of which are provided with rings 10 freely engaging the ears 7 of the body-member.

11 in Fig. 1 is a portion of a sucker-rod, which for the purpose of illustration is taken to show the part upon which the elevator is used. It is obvious, however, as stated hereinbefore, that said part may be the tubing or the well casing or any other pipe or rod.

The sucker-rod 11 is shown as provided with the usual pin member 12 of the coupling, the complementing box member of said coupling not being here shown. It will be seen that when the elevator is lifting or supporting the sucker-rod, the shoulder 13 of the coupling 12 rests on top of the latch-member 2, which is then down to its seat and locked on the body member.

The operation of the elevator is as follows:—In order to engage and lift rod sections lying on their sides, the elevator is slipped along the section, with the body

95

100

105

groove 4 following and partially embracing the rod. In this movement the friction of the rod section against the edge of the bottom of the latch-member which overlies the 5 groove and is preferably beveled as shown at 14, is sufficient to automatically raise the latch member about its pivotal bolt 8, and as soon as it is lifted far enough, the elevator body drops clear down upon the rod 10 section, the latter then lying in the base of the body groove 4. Thereupon the latch member drops back by gravity over the rod, to its locking position, and the rod section is then wholly confined in the alined 15 bases of both grooves and can be lifted.

When the rod is in a vertical position, and the elevator is slipped along it with its body groove following the rod, the coupling of the rod catches on the under side of the 20 latch member and lifts it, the latch thereupon falling back by gravity as the rod enters the base of the groove.

The latching is, therefore, always automatic and positive, and it is impossible for 25 the rod to become disengaged accidentally.

15 indicates a finger groove, one on each side of the latch member, to enable said member to be readily lifted by hand if required.

30 It will be seen from Fig. 1 that the elevator is locked when under load. As all elevators are a sliding fit on the rod, pipe or casting, and carry the load by coming up against the coupling, it will readily be seen that with 35 my elevator, the load locks the same positively and without stress on any hinge or pin joint.

The elevator cannot be sprung out of shape and thereby rendered useless. The load is 40 carried by the solid rigid single-piece body which cannot be sprung, as is the case in other elevators where the load is imposed upon hinged joints or pin connected latches.

45 My elevator combines the essential advantages of the single link type with the latching type. Most elevators are double link type requiring two hands to engage the links with the hoisting hook, while the single link type may be engaged with the hoisting 50 hook with one hand, leaving the operator free to catch the hook with his other hand and swing it into position. Previous elevators which are of the latching type require two links, while those having one link are 55 not provided with the latching feature.

Another great objection to the double link 60 type is the danger of only one link becoming engaged with the hook. This springs the elevator and may cause the rods to be dropped. It also may spring the latch and make it inoperative. In my elevator, however, there is no hinge subjected to load.

From the foregoing it will be seen that 65 the elevator herein described combines the single link with positive latching. The

latching is automatic, and the latch opens freely and practically automatically in the operation of engaging the rods. The elevator is positively locked when under load. The load is carried by a single piece body without distorting stresses to any hinge or latching device. The elevator cannot become jammed and thus rendered inoperative. It can be operated with one hand, and the operation is both easy and rapid.

I claim:

1. An elevator for the described purposes, comprising a rigid block forming a body-member, having a radial groove extending from top to bottom, and opening out at the side; a latch-member hinged to the top of the body-member, and adapted to close down upon and to swing away from said top, said latch-member having a radial groove extending from top to bottom and opening out at the side, said groove being in a plane at right angles to the groove of the body member, the bases of the two grooves being alined when the latch member is closed down on the body-member; and suspending connections for the body-member.

2. An elevator for the described purposes, comprising a rigid block forming a body-member, having a radial groove extending from top to bottom, and opening out at the side; a latch-member hinged to the top of the body-member, and adapted to close down upon and to swing away from said top, said latch-member having a radial groove extending from top to bottom and opening out at the side, said groove being in a plane at right angles to the groove of the body member, the bases of the two grooves being alined when the latch member is closed down on the body-member; and a single suspending link engaging the sides of the body-member.

3. An elevator for the described purposes, comprising a rigid block forming a body-member, having a radial groove extending from top to bottom and opening out at the side, the top of said member having guide-lugs on each side of said groove; a latch-member hinged at one side to and playing over one of said guide lugs, and at the other side fitting and playing over the other of said guide lugs, whereby it is adapted to swing away from the top of the body member and to seat and lock itself thereon against lateral movement, said latch-member having a radial groove extending from top to bottom and opening out at the side, said groove being in a plane at right angles to the groove of the body member, the bases of the two grooves being alined when the latch member is closed down on the body-member; and suspending connections for the body-member.

4. An elevator for the described purposes, comprising a rigid block forming a body-

member, having a radial groove extending from top to bottom and opening out at the side, the top of said member having guide-lugs on each side of said groove; a latch-member hinged at one side to and playing over one of said guide lugs, and at the other side fitting and playing over the other of said guide lugs whereby it is adapted to swing away from the top of the body member and to seat and lock itself thereon against lateral movement, said latch-member having a radial groove extending from top to bottom and opening out at the side, said groove

being in a plane at right angles to the groove of the body member, the bases of the two 15 grooves being alined when the latch member is closed down on the body-member; and a single suspending link engaging the sides of the body-member.

In testimony whereof I have signed my 20 name to this specification in the presence of two subscribing witnesses.
